UNITED STATES PATENT OFFICE.

NICHOLAS H. JACOVATOS, OF NEW YORK, N. Y.

LIQUID-FLOW GOVERNOR.

Application filed April 5, 1924. Serial No. 704,425.

My invention relates to means for governing the flow of liquids from pipe lines or reservoirs, and more particularly to means for governing such flow when there is a 5 multiple source of supply.

One of the objects of my invention is to provide a governor whereby the flow may be limited to one or more of the sources of multiple supply. Another object is to selectively 10 combine the several units of such supplies. A third object is to regulate the proportions in which such units may be combined. Other objects will become apparent from the detailed description which 15 follows.

Figure 1 is a view of one of the forms of my invention in cross section through a vertical plane. Figure 2 is a top view of the same form, partly in cross section through 20 the line 2—2 of Figure 1. Figure 3 is a detail of the same form in cross section along the line 3—3 of Figure 1. Figures 4 and 5 are cross sections of another form of my invention, taken vertically and horizontally, 25 respectively, Figure 5 being a cross section along the line 5—5 of Figure 4. Figure 6 is a front view of still another form of my invention, partly in cross section. Figures 7 and 8 are details of the form shown in 30 Figure 6, being cross sections along the lines 7—7 and 8—8 of Figure 6, respectively. Figure 9 is a front view of another modification of my invention, partly in cross section. Figure 10, with its steps *a*, *b*, *c*, *d*, 35 and *e*, and Figure 11, with its steps *a*, *b* and *c*, schematically illustrate the operation of my device, as will be duly explained below.

Referring more particularly to Figures 1 and 2, 1' and 1'' are two chambers of a 40 vessel separated from one another by the valve seat 2 formed partly by the walls of said chambers; into said valve seat 2 fits loosely the valve 3 which may be turned by means of the handle 4. Into the valve 45 seat 2 enter the supply pipes 5' and 5'' conveying different liquids to the chambers 1' and 1'' respectively through the passage ways 6' and 6'' in the valve 3 and the outlets 7' and 7'' of said passage ways, and the 50 ports of entry 8' and 8'', to said chambers, when the outlets 7' and 7'' register with the ports of entry 8' and 8'', as they do in the drawing. The chambers 1' and 1'' have exit ports 9' and 9'' which register with the 55 slots 10, 10, in the lower, hollow end of the valve 3 when the valve 3 is turned to a

proper angle. When the slots 10, 10, register with the exit ports 9', 9'', the outlets 7', 7'' are out of register with the entry ports 8', 8''. However, it is not necessary 60 that both slots 10, 10 register simultaneously with the exit ports 9', 9'', as may be gathered by inspection of Figure 3. This detail Figure 3 shows that the slots 10, 10, as well as the exit ports 9', 9'', are not diametrically opposed to one another, so that it is possible to turn the valve either into a position where only one of said slots 10 registers with one or the other of the exit ports 9', 9'', or into a position where both 70 slots 10, 10 register with said two exit ports, or, if so desired, one or both slots 10 may only partially register with the exit ports. On top of each chamber 1', 1'' are covers 11', 11'', tightly fastened thereto by means of 75 screws or bolts 12, and bearing the plungers 13', 13'', of standard construction and adjustable to various heights by means of the threaded members 14', 14''. The movement of a plunger 13' is possible so long as 80 the cone 15' has not reached the corresponding conical seat in the threaded member 14', as shown in Figure 1, on the left side. On the right side, the plunger 13'' has reached the limit of its motion, the cone 15'' having 85 reached its seat in the member 14''. The entire governor, including the two chambers 1', 1'', and valve 3, may be attached to any suitable place by means of the brackets 90 16, 16.

The only difference between the forms shown in Figure 1 and in Figure 6 is in the arrangements of the slots in the hollow end of the valve 3. As shown in Figure 6, in conjunction with detail Figures 7 and 8, the 95 two slots 10^a and 10^b are at different heights, for purposes which will be explained later.

In the form of my invention shown in Figure 9, I use only one chamber, 1'', with all the elements appertaining thereto as in 100 the forms disclosed in Figures 1 and 6, but the other chamber 1' is replaced by the pipe 17 which takes place of the entry port 9'.

In Figures 4 and 5, I show another modification of my invention wherein both the 105 chambers 1' and 1'' are eliminated and the liquid is supplied to the valve directly from several sources (four only shown in the drawings) by means of the pipes 18, 19, 20, 21. In this case, i. e., when the number of 110 supply sources is greater than three, I prefer to use a sleeve 22 between the valve 3

and the valve seat 2, a second handle, 23, being provided to turn the sleeve 22 independently of the valve 3. The sleeve 22 has a suitable number of portholes 24 which may 5 register with the slot 25 in the valve 3, at which times the liquids entering through one or more of the pipes 18, 19, 20, 21, according to the position of the sleeve, will emerge through the open end 26 of the 10 valve 3.

The five schematic figures of Figure 10 show various positions of a valve with regard to the valve seat when there are three sources of supply, 1, 2 and 3 being three exit 15 ports from reservoirs or pipes, and 4, 5 and 6 being three slots in the hollow open end of the valve. It will be seen that in the position, Figure 10^a, no liquid can pass through; in the position of Figure 10^b, only liquid from source 1 may pass; in the position, Figure 10^c, only liquids from sources 1 and 3 may pass; in the position, Figure 10^d, liquids may pass from all three sources; and in the position, Figure 10^e, only liquids 25 from sources 2 and 3 may pass. It should be noted that intermediate positions of the valve will allow some or all of the liquids to be discharged only partially, by incompletely registering the slots and ports.

The three schematic figures of Figure 11 show some of the positions of a valve with regard to the valve seat when the particular object in view is to not only shut off one or the other of two sources of supply, but to 35 be able to regulate the proportions in which the two supplies may be combined in the discharged flow. Figure 11^a shows the position of such a valve when both supplies are shut off; in Figure 11^b, only one of the two sources is allowed to furnish the discharge flow; and in Figure 11^c, one source is permitted to discharge in full, while the other discharges only a proportion of the full amount which it is capable of discharging. 40 Other positions, not shown, would furnish all sorts of proportions between the two supplies that one may desire to obtain. Of course, the ports and slots may be arranged in a great many other ways. The drawings 45 here shown are merely for the purpose of illustration.

The method of operating my governor will now be briefly described. Considering first the form shown in Figures 1 and 2, I 55 adjust the two plungers 13', 13'' to different heights by regulating the positions of the threaded members 14', 14''. The handle 4 is turned to a position whereby the ports of entry 8', 8'' register with the outlets 7', 60 7'' of the passage ways 6', 6''. The two chambers 1', 1'' will fill up to different levels, according to the adjustment of the plungers, the inflow of liquids being stopped when the cones 15', 15'' reach their respective 65 seats in the members 14', 14''. Com-

pression of air above the liquids in the chambers will stop further inflow. Then I turn the handle 4 to a position where the ports of exit, 9', 9'' register with the slots 10, 10, whereby the chambers will be emptied of 70 their contents through the open end of the valve 3. While the chambers are being emptied the ports of entry 8', 8'' are out of register with the outlets 7', 7''.

In operating the form shown in Figure 75 6, the chambers will not be completely emptied, each chamber being reduced of its contents only down to the corresponding level of the slot 10^a or 10^b.

I may, of course, have more than two 80 chambers in my governor. In the case of three such chambers, I use an arrangement of exit ports and slots illustrated in Figures 10^a to 10^e. Or, I may have only one chamber, as shown in Figure 9, the second supply 85 coming directly through a pipe 17. This arrangement is well adapted, for instance, to soda fountains. The supply of water or carbonated water would be obtained through the pipe or opening 17, while a supply of 90 syrup or phosphate, regulated as explained in regard to the operation of the chambers in the other forms of my invention, would be secured through the port of exit 9''. Of course, in this case, also, I may use slots at 95 various heights, as in the case of Figure 6. Finally, I may dispense with chambers altogether, as in the case illustrated in Figures 4 and 5. When I have only two or three sources of supply, the sleeve 22 is not necessary. I would, in this case, use an arrangement as shown for the left side of Figure 9, and the schematic slot arrangement of Figures 10^a to 10^e (for three sources), or the slot arrangement of Figures 11^a to 11^c 105 (for two sources). But when I have more than three sources of supply, I prefer to use a sleeve 22, as illustrated in Figures 4, 5.

I claim:

1. In a liquid flow governor, a chamber 110 and a valve seat, a valve turnable in said seat and having a hollow open end, means for turning said valve, an entry port into said chamber through an opening in said valve seat, a passage way in said valve having an outlet adapted to register with said entry port as said valve is turned, means for conveying a liquid to said chamber through said passage way, an exit port from said chamber through a second opening in said valve seat, slots in the hollow end of said valve at various levels thereof and adapted to register with said exit port as said valve is turned, and means for conveying a second liquid to said hollow end of said valve when 115 one of said slots registers with said exit port, said outlet and entry port being out of register when said exit port registers with one of said slots, and vice versa.

2. In a liquid flow governor, two cham- 120

- bers and a valve seat, a valve turnable in said seat and having a hollow open end, means for turning said valve, entry ports into said chambers through openings in said 5 valve seat, passage ways in said valve having outlets adapted to register with said entry ports as said valve is turned, means for conveying liquids to said chambers through said passage ways, means for regulating 10 the amount of liquid which each chamber may receive, exit ports from said chambers through other openings in said valve seat, and slots in the hollow end of said valve adapted to register with said 15 exit ports as said valve is turned, said entry ports and outlets being out of register when said slots and exit ports register, and vice versa.
3. In a liquid flow governor, two chambers and a conically shaped valve seat, a 20 valve loosely fitting into said seat and turnable therein, said valve having a hollow open end, means for turning said valve, an entry port into each one of said chambers 25 through an opening in said valve seat, passage ways in said valve having outlets adapted to register with said entry ports as said valve is turned, means for conveying liquids to said chambers through said passage ways, 30 means for regulating the amount of liquid which each chamber may receive, exit ports from said chambers at different levels through other openings in said valve seat, and slots in the hollow end of said valve 35 adapted to register with various ones of said exit ports as said valve is turned and according to the angle by which said valve is turned, said entry ports and outlets being out of register when said slots and said 40 various exit ports register, and vice versa.
4. In a liquid flow governor, a chamber and a valve seat, a valve turnable in said seat and having a hollow open end, means for turning said valve, an entry port into said 45 chamber through an opening in said valve seat, a passage way in said valve having an outlet adapted to register with said entry port as said valve is turned, means for conveying a liquid to said chamber through 50 said passage way, means for regulating the amount of liquid which said chamber may receive, and exit port from said chamber through a second opening in said valve seat, a slot in the hollow end of said valve adapted to register with said exit port as said 55 valve is turned, and means for conveying a second liquid to said hollow end of said valve when said slot and said exit port register, said outlet and entry port being out of register when said slot and exit port register, 60 and vice versa.
5. In a liquid flow governor, a multiplicity of chambers and a valve seat, a valve turnable in said seat and having a hollow open 65 end, means for turning said valve, an entry port into each chamber through an opening in said valve seat, passage ways in said valve having outlets adapted to register with said entry ports as said valve is turned, means for conveying liquids to said chambers through said passage ways, means for regulating the amount of liquid which each chamber may receive, exit ports from said chambers through other openings in said valve seat, and slots in the hollow end of said valve 70 adapted to partially or completely register with said exit ports as said valve is turned, said entry port into a chamber and the corresponding outlet from said valve being out of register when the corresponding slot and exit port register, and vice versa.
6. The combination with a reservoir, of liquid supplying means independent of said reservoir, a valve provided with a single outlet, a multiplicity of inlets into said valve, 75 some of said inlets being from said reservoir and some from said independent liquid supplying means, and means for selectively connecting one of said multiplicity of inlets to said outlet.
- 85 7. The combination with a reservoir, of liquid supplying means independent of said reservoir, a valve provided with a single outlet, a multiplicity of inlets into said valve, some of said inlets being from said reservoir and some from said independent liquid supplying means, and means for selectively connecting some of said inlets to said outlet.
- 90 8. The combination with a reservoir, of liquid supplying means independent of said reservoir, a valve provided with a single outlet, a multiplicity of inlets into said valve, partly from said reservoir and partly from said independent liquid supplying 95 means, said outlet being selectively registrable with one or more of said inlets, and means for regulating the relative flow from said reservoir and from said independent liquid supplying means through said outlet.
- 100 9. A liquid flow governor comprising a multiplicity of chambers, each chamber being independently supplied with a liquid, a valve having a single outlet, inlets from said chambers into said valve, and means for selectively connecting said outlet with one or more of said inlets.
- 110 10. A liquid flow governor comprising a multiplicity of chambers, each chamber being independently supplied with a liquid, a valve having a single outlet, inlets from said chambers into said valve, said outlet being selectively registrable with one or more of said inlets, and means for regulating the relative rate of flow of said liquids through said outlet.
- 115 120 11. In a liquid flow governor, a reservoir, a valve provided with a single outlet, a multiplicity of inlets into said valve, means for conveying liquids to said inlets from said 125 130

- reservoir and from a source independent thereof, and means for regulating the proportions in which the liquids from said reservoir and from said independent source 5 may flow through said outlet.
12. In a liquid flow governor, a multiplicity of chambers, a valve having a single outlet, inlets from said chambers into said valve, and means operatively connected with 10 said outlet and said inlets for regulating the proportions in which said chambers contribute to the flow through said outlet.
13. In a liquid flow governor, a chamber, liquid conveying means independent of said 15 chamber, a valve having a single outlet, a multiplicity of inlets into said valve at different levels thereof, some of said inlets being from said chamber and some from said independent liquid conveying means, and 20 means for selectively connecting said outlet with one or more of said multiplicity of inlets.
14. In a liquid flow governor, a multiplicity of chambers, a valve having a single 25 outlet, inlets from said chambers into said valve at different levels thereof, and means for selectively connecting said outlet with one or more of said inlets.
15. In a liquid flow governor, a chamber, 30 a valve having a single outlet, a multiplicity of inlets into said valve at different levels thereof, some of said inlets being from said chamber, said outlet being registerable with one or more of said multiplicity of inlets, and means for regulating the rate of flow 35 and the proportion of the liquid contributed by said chamber to said flow through said outlet.
16. The combination with a multiplicity of liquid conveying means, of inlets at different levels and a single outlet therefor, and means for associating an inlet with one or another of said liquid conveying means. 40
17. The combination with a multiplicity of means for conveying liquids, of inlets 45 at different levels and a single outlet therefor, and means for regulating the relative rates of discharge of said liquids through said outlet, by controlling the effective areas of said inlets.
18. In a liquid flow governor, a multiplicity of chambers, each chamber adapted to be supplied independently with a liquid, outlets from said chambers at different levels, and means for regulating the flow of 50 said liquids from said chambers by controlling the effective areas of said outlets.
19. In a liquid flow governor, a multiplicity of chambers adapted to receive independent supplies of liquids, outlets from 55 said chambers, and means for regulating the flow of said liquids from said chambers by controlling the hydraulic heads of said liquids and the effective areas of said outlets.

New York, April 2, 1924.

NICHOLAS H. JACOVATOS.
